UNITED STATES PATENT OFFICE.

FREDERICK E. STRICKLAND, OF ALEXANDRIA, LOUISIANA.

BLOTTER ATTACHMENT FOR FOUNTAIN PENS.

Application filed April 26, 1924. Serial No. 709,205.

This invention relates to new and useful improvements in blotters, and has reference more particularly to an attachment for a fountain pen cap, wherein the blotter is 5 normally disposed in the cap and readily extensible therefrom to an operative position, in a simple and efficient manner.

One of the important objects of the present invention is to provide a device of the 10 above mentioned character, wherein a rotary blotter is adapted for slidable movement in a fountain pen cap, means being associated with the fountain pen cap and the blotter supporting means for facilitating the 15 slideable movement of the blotter with respect to the fountain pen cap, in moving the same into an operative or inoperative position.

A still further object of the present invention is to provide a device of the above 20 mentioned character, wherein the blotter supporting means includes a closure adapted for cooperation with the outer open end of the fountain pen cap when the blotter is in an inoperative position.

25 A still further object of the invention is to provide a device of the above mentioned character which is simple in construction, inexpensive, strong and durable, and further well adapted for the purposes for which it is 30 designated.

Other objects and advantages of this invention will become apparent during the course of the following description.

In the accompanying drawing, forming 35 a part of this specification, and in which like numerals designate like parts through the same:

Figure 1 is a side elevation of a fountain pen cap with my invention associated therewith, and in an inoperative position.

40 Figure 2 is a longitudinal sectional view thereof.

Figure 3 is a longitudinal sectional view, 45 showing the blotter in an operative position, and

Figure 4 is a transverse section, taken approximately upon the line 4—4 of Figure 1.

In the drawing, wherein for the purpose 50 of illustration is shown the preferred embodiment of my invention, the numeral 1 designates a fountain pen cap, which is of the usual construction, and in the present invention has its respective ends open. The 55 inner end of the cap 1 is internally thread-

ed, as shown at 2, for engagement with the external threads on the fountain pen in the usual manner, and as the same forms an important part of the present invention, it is not thought necessary to further go 60 into detail relative to the same. Provided in the wall of the fountain pen cap is the longitudinally extending slot 3, and the same extends from a point adjacent the inner end of the fountain pen cap, to the outer end 65 thereof, in the manner as clearly illustrated in Figures 1, 2, and 3 of the drawings. The provision of the longitudinally extending slot 3, forms a guide means in connection with the blotter supporting member, and 70 the latter will be hereinafter more fully described. A suitable band, such as is shown at 4 is adapted to extend around the outer end of the cap 1.

75 Adapted for slidable movement within the fountain pen cap 1, is the sleeve 5 and extending outwardly from the sleeve 5 toward the outer end of the fountain pen cap 1 is the spring metallic strip or band 6. Any suitable fastening means may be 80 provided for securing the inner end of the band to the sleeve and the same is preferably supported thereon so as to be disposed directly beneath the longitudinally extending slot 3. Extending upwardly from the sleeve 5 at the inner end of the metallic band 6, 85 is the thumb slide 7, the same being adapted to extend through the longitudinally extending slot 3 and provides a means whereby the slide and band 6 may be moved longitudinally with respect to the cap 1. The outer end of the metallic strip or band 6 carries thereon a closure 8, the same being of such a construction as to cooperate with the open outer end of the cap to close the 90 same, when the sleeve 5 is in its innermost position within the cap, in the manner as more clearly shown in Figures 1 and 2 of the drawings. When in this position, the closure 8 will abut the outer edge of the 100 ring or band 4.

Supported by the intermediate portion of the metallic strip or band 6 is the bracket 9, and the same provides a means for supporting the rotary blotter 10, in the manner well known in the art. The supporting bracket 9 is so secured to the intermediate portion of the strip 6, by the fastening means, as shown at 11, so as to have the rotary blotter 10 extending longitudinally and the blotter is 110

further arranged as to be readily and easily moved to an operative or inoperative position, as will be presently described.

Normally the blotter 10 and the supporting strip 6, which carries the supporting bracket 9, in which the rotary blotter 10 is journaled, are arranged in the cap 1, and the sleeve 5 will be in its innermost position and the closure 8 will close the outer end of the cap. When it is desired to use the blotter, the thumb slide 7 is moved away from the inner end of the fountain pen cap and simultaneously will cause the closure 8 to move outwardly, out of engagement with the outer end of the cap and further cause a blotter 10 and the sleeve 5 to move to the position as shown in Figure 3 of the drawing, wherein the rotary blotter is extended to an operative position, whereby the same may be contacted with and rolled upon the surface to be blotted. It is to be understood that the outer portion of the strip 6 is bent upwardly, so that when the rotary blotter 10 is in an extended position, the closure 8 will be raised, in the manner shown in Figure 3, so as not to interfere with the operation of the blotter or cause the closure to come in contact with the surface to be blotted. The band 4 will limit the outward movement of the sleeve and thumb slide 7, so as to prevent any possibility of the rotary blotter being moved off of the fountain pen cap.

After the rotary blotter has been used, the thumb slide 7 is returned to its normal position, simultaneously retracting the sleeve 5 and the spring strip or band 6 carried thereby, together with the rotary blotter 10, so that the same will return to their normal positions within the fountain pen cap, the closure 8 again closing the outer end of the fountain pen cap and permitting the cap to be screwed onto the pin section of the foun-

tain pen, in the usual manner. The provision of the sleeve 5 provides a means whereby the pen point will be received within the cap, without causing any injury thereto, or to the blotter attachment.

It will thus be seen from the foregoing description that a rotary blotter attachment for fountain pens has been provided, which is very simple in construction, the parts being further so arranged as to enable the same to be readily and easily moved to an operative position or an inoperative position, as is desired. Any suitable material may be used in constructing my blotter attachment and I do not wish to limit myself to any particular kind of material, which is to be used.

While I have shown the preferred embodiment of my invention, it is to be understood that various changes in the size, shape, and arrangement of parts, may be resorted to, without departing from the spirit of the invention and the scope of the appended claim.

Having thus described my invention, what I claim is:

In combination, an open ended cylinder having a longitudinally extending slot, a sleeve slidably mounted in the cylinder and provided with a projection extending through the slot, by which the sleeve may be moved in a limited manner longitudinally of the cylinder, a strip extending from the sleeve longitudinally of the cylinder and disposed to move under the slot when the sleeve is moved inwardly of the cylinder for the purpose of closing the slot, a closure carried by the end of the strip, and an article supporting bracket attached to the strip between the sleeve and the closure.

In testimony whereof I affix my signature.

FREDERICK E. STRICKLAND.
